CLAIM

The ornamental design for a curved infrared burner, as shown and described.

DESCRIPTION

FIG. 1 is a perspective view of a curved infrared burner.

FIG. 2 is a top plan view of the curved infrared burner of FIG. 1.

FIG. 3 is a bottom plan view of the curved infrared burner of FIG. 1.

FIG. 4 is a left side elevational view of the curved infrared burner of FIG. 1.

FIG. 5 is a right side elevational view of the curved infrared burner of FIG. 1.

FIG. 6 is a front elevational view of the curved infrared burner of FIG. 1; and,

FIG. 7 is a rear elevational view of the curved infrared burner of FIG. 1.

The broken lines in the drawings represent environmental subject matter and form no part of the claimed design.
